UNITED STATES PATENT OFFICE.

JOHN ERNEST BURKHARDT, OF BATH, MAINE, ASSIGNEE TO JOHN J. WARREN, OF BROWNVILLE, NEW YORK.

CHAIN FOR WOOD-PULP GRINDERS.

Application filed November 8, 1924, Serial No. 743,617, and in Canada October 28, 1924.

This invention relates to feed chains particularly adapted for use in wood pulp grinders of the magazine type.

In United States Patent No. 1,465,069, the inventor has described a wood-pulp grinder of the magazine type in which the wood is continuously forced against the grindstone by means of endless feed chains which move down the inner face of the magazine, and grip the wood by means of projecting spurs situated at the forward or lower ends of the chain links. By reason of the fact that these projections are situated at the forward ends of the links they are swung away from the wood as the chains turn about their lower sprockets, whereas if they were placed on the rear or upper ends of the links they would tear into the wood at that point, thus not only consuming power unnecessarily, but making slivers, I have found these chains to operate well in practice. The specific form illustrated in the patent, however, is relatively expensive to manufacture inasmuch as the projecting, wood-gripping spurs are not integral with the links but are affixed thereto. It is therefore an object of the present invention to design a feed chain the links of which, with their associated spurs, can be made less expensively than the separate spur type. I attain this object by forging both link and spur from a single piece of metal. This construction is not only cheaper than the one illustrated in the patent, but being unitary is also somewhat more rugged.

The actual wood-gripping face of the spurs illustrated in the patent is also relatively narrow, which, although sufficient when working with firm, sound wood is likely to cause the spurs to crush through the soft and rotten logs which must sometimes be ground. It is a further object of this invention to design a feed chain adapted for use in grinding soft or rotten wood. I attain this object by widening the wood-contacting face of the spurs so that the pressure exerted by them is distributed over a greater area of the wood.

It is a further object of the invention to make a generally improved chain for the purpose indicated.

In the accompanying drawings I have illustrated certain preferred embodiments of my invention which I shall now describe. In these drawings, Figure 1 is a front eleva-

tion of my improved chain. Figure 2 is a side elevation of the same chain. Figure 3 is a front elevation of a modified form of chain in which the wood-gripping elements are of a somewhat different shape, and, Figure 4 is a perspective view of the lower end of one of the links which go to make up the chain shown in Figure 3. In these drawings I have not illustrated the wood-pulp grinder itself, it being understood that these chains are adapted to operate in a grinder similar to the one illustrated in the above-mentioned U. S. patent.

The chain illustrated in Figures 1 and 2 comprises a series of parallel links 1 journaled upon connecting pins 2 and spaced apart by means of cylindrical rollers 3, likewise journaled upon the pins 2. These rollers 3 are adapted to roll upon vertical track-ways on the inner face of the magazine and prevent contact of the chain links therewith. The lower end of each link is provided with a spur or projection 4 integral therewith and having a substantially flat wood-contacting face 5 of a width equal to that of the link of which it forms a part. This wood-contacting face is, however, slightly convex in the plane in which the chain operates, as clearly shown in Figure 2, and is preferably made part of a cylinder 75 the axis of which is coincident with that of the rear or farther pin of the same link. This facilitates the withdrawal of the spurs from contact with the wood as the links swing outwardly about the lower sprocket 90 with minimum damage to the wood. The horizontal center line of the spurs is also situated well below the center of the pin 2 upon which the lower end of the link in question is journaled. By means of this 95 construction the effective length of each link is increased, which means that the column of wood can be carried just that much closer to the grindstone before the pressure exerted by the lowermost spur is withdrawn. This 100 is advantageous inasmuch as the less the distance intervening between the upper face of the stone and the point where the chains leave the wood, the less the opportunity for counter-arching, as clearly described in 105 United States Patent No. 1,505,757. The triangular form of the spurs and the fact that they are made integral with the links greatly increases their strength.

The chain illustrated in Figures 3 and 4 is 110

similar to the one in Figures 1 and 2, except that the spurs 4 are extended laterally on either side of the links so that the area of the wood-contacting face 5 is increased. Except for this difference, the chains are identical and function in the same manner.

The links illustrated in these drawings are preferably made by drop-forging in a manner which is well understood in the art, and which need not be described in detail here.

Among the advantages inherent in my novel chain are the following:—First, the wood-gripping spurs being integral with the links, each complete link can be made more cheaply than a link which is equipped with a separate spur which must be affixed thereto. Second, the integral construction of spur and link and the shape of the spurs make for a stronger and more rugged construction. Third, the wood-gripping spurs are situated beyond and below the center line of the pin upon which the lower end of the link is journaled, thus increasing the effective length of the link and making it possible to continue the stoneward pressure of the chains to a point more closely adjacent the stone than would be possible if the spur were situated farther back along the link. Fourth, the wood-contacting face of the spur, being slightly convex, preferably having its center of curvature coincident with the center of the farther pin of the same link, is disengaged from the wood as the chain moves about the lower sprocket with a minimum of effort and damage to the wood. Fifth, the wood-contacting face of the spur is not less than the width of the link and as illustrated in Figures 3 and 4, may be much wider. This is particularly advantageous in grinding soft or decayed

wood, as it distributes the chain pressure over a larger area and minimizes the chances of crushing or tearing through the wood.

I claim:

1. A feed chain for wood-pulp grinders comprising a series of links and wood-contacting projections on the forward ends thereof having wood-contacting faces of a width greater than the thickness of the links. 45

2. A feed chain for wood-pulp grinders comprising a series of links having wood-gripping spurs on the forward ends thereof, the wood gripping face of the spurs being slightly convex in the plane in which the chain operates. 50

3. A feed chain for wood-pulp grinders comprising a series of links, connecting pins upon which the links are journaled at each end, wood-contacting projections on the forward ends of the links integral therewith and situated beyond the forward connecting pins. 60

4. A feed chain for wood-pulp grinders comprising a series of links, and wood-contacting projections on the forward ends thereof integral therewith and having wood-contacting faces of a width greater than the thickness of the links. 65

5. A feed chain for wood-pulp grinders comprising a series of links, connecting pins 70 upon which the links are journaled at each end, wood-contacting projections on the forward ends of the links having cylindrical wood-contacting faces, the axis of each such cylindrical face being coincident with that 75 of the axis of the farther pin of the same link.

In testimony whereof I affix my signature.

JOHN ERNEST BURKHARDT.
